UNITED STATES PATENT OFFICE.

OTTO WETTSTEIN, OF ROCHELLE, ILLINOIS.

DESIGN FOR A SPOON, &c.

SPECIFICATION forming part of Design No. 21,334, dated February 2, 1892.

Application filed November 20, 1891. Serial No. 412,569. Term of patent 3½ years.

To all whom it may concern:

Be it known that I, OTTO WETTSTEIN, a citizen of the United States, residing at Rochelle, county of Ogle, State of Illinois, have invented and produced a new and original Design for the Handles of Spoons, Knives, and Forks, of which the following is a specification, reference being had to the drawing, forming a part thereof.

10 The drawing is a representation of a spoon embodying my design.

The leading features of this design consists in a spoon provided at the upper extremity of its handle with the representation of the

face of Robert G. Ingersoll and at its lower extremity with a bowl which is of heart shape. The likeness of Robert G. Ingersoll is formed on the face of the handle of the spoon, the outline of the outer end of the handle conforming to that of the likeness. 20

I claim as my invention—

The design for a spoon, as herein shown and described.

OTTO WETTSTEIN.
